WILLIAM H. SMYTH, OF BERKELEY, CALIFORNIA.

HIGH-SPEED SELF-LAYING TRACK VEHICLE.

Application filed July 28, 1923. Serial No. 654,432.

This invention relates to the class of vehicles that lay down a supporting track as, and upon which, they travel. It has for its main object to notably increase the capability for speed and traction in this type of vehicle. Incidental to the main purpose, another object is to reduce the number of actively load-bearing parts in the wheel-base while increasing its effective length and responsiveness to changes in the ground surface contour and load conditions; also to cushion the machine under these varying conditions and especially to eliminate the destructive jars incident to track-chain joint-buckling and the sharp kinking of the chain-hinge joints in passing over localized resistant obstructions. Still another object is to so construct the device that the parts shall be adapted to large-scale manufacture and easy to assemble, to dismember or to replace worn parts.

A typical expression of my invention that accomplishes these objects is shown in the accompanying drawings wherein:

25 Fig. 1 shows a side elevation, parts being removed for better illustration;

Fig. 2 shows a side elevation of a partial assemblage illustrating modification in some details of construction;

30 Fig. 3 shows a transverse section of the form illustrated in Fig. 2, on the dotted line $x-x$;

Fig. 4 shows a plan view, parts being broken away for better illustration;

35 Fig. 5 shows a detail of construction, on a somewhat enlarged scale.

As the track-assembly alone distinguishes the self-laying-track type from the "round-wheeler" form of vehicle, the other parts being common to both types, (and the construction of these common parts being within the knowledge of mechanics skilled in the art), I will confine my description to those parts of the structure directly affected by my invention. But, in what follows, it is to be understood that the needed and omitted parts known to the art are assumed to be present and to be of such form and character as best serves the needs and purposes of the constructor and user.

With this understanding, A—A, in Fig. 1 and A¹—A¹⁰ in Fig. 2, represent the frame-

work pertaining to a self-laying-track vehicle. It carries journal-box B, shaft C, and power-wheel D.

55 E—E¹ is a curved guide-rail preferably formed of an upper and a lower rail hinged together and to the frame at E², from which point the members E and E¹ curve upward and downward respectively and rearwardly into proximity to the periphery of wheel D, with which the rail members constitute a substantially continuous flexibly-hinged and resilient guide-way for an endless track-chain, thus providing means to maintain the upper and lower folds of the chain in the same plane of travel.

The upper member of the curved guide-rail may be provided with a flexible extension, shown as a leaf-spring e, in Fig. 2. The lower member is shown formed in two, 70 spring-actuated, resilient sections flexibly-hinged together at e³.

The second section e², as shown in Fig. 1, may be laminated to give it additional flexibility and resilience.

75 In Figs. 2 and 3, the second resilient section marked e²⁰, is shown as formed of stock channel iron. The lower rail member E¹, may also have secured thereto, angle-iron 80 lateral extensions projecting over the tracks substantially the full width of the unoccupied space between the frame members to form dirt-excluding rail-covers, as shown in section at e⁴. The flexibly-hinged rail-member E¹, may also be provided with lateral abutments e⁵, contacting the frame members and vertically movable with reference thereto, to prevent lateral displacement of the track in its ground run.

85 F, is a load-bearing track-chain of ordinary construction, other than that it is provided with antifriction rollers F¹, journalled thereon below its track surface. The chain-track is preferably twin-track, being made up of laterally adjacent parallel tracks f—f¹ attached to suitable ground-bearing tread-plates f². The track-chain F, is trained about the guide-way formed by the guide-rails E—E¹, and power-wheel D, around which guide-way the chain travels on its antifriction rollers F¹, in the manner indicated in the various views.

90 G—G¹, are truck wheels, preferably

flanged, travelable upon the ground run of the track-chain F. These wheels constitute the sole support of the machine. They are shown formed as twin wheels G—G, G¹—G¹ 5 to coact with the twin-track f—f¹, Fig. 4. The twin members of the support wheels G and G¹, are concentric, each pair on an axle g¹, and each axle is journalled in a suitable box or bearing g². H—H are bracket 10 arms, one of which is secured to each of the journal-boxes g², and extends downwardly to the lower guide-rail section e², to which it is pivotally connected, as shown in Fig. 1, thus forming a two-point support independently movable truck wheel-base. 15

I is a spring interposed between the journal-boxes g²—g², and the frame of the machine, to transfer the load or weight of the motor parts resiliently to the support wheels 20 G—G¹. In the present expression of my invention, it is shown as a semi-elliptical spring with one of its ends pivotally connected to one of the journal-boxes g², at i, its other end being similarly connected to 25 the other journal-box.

To attach the spring I, to the frame of the machine, a short beam A², extends across the frame members, to which the beam is secured, and on the top of the beam the 30 spring is strongly attached by a clamping plate a, and bolts a¹—a¹. For additional rigidity in the framework, the lower flange of the beam A², may be bent downward at each of its ends to form lateral abutments 35 to the frame members as shown at A⁵, Figs. 3 and 5, and a tie-rod a², provided, extending from side to side through these members. When this tie-rod is employed the bolts a¹—a¹, may extend down thereto, as 40 shown at a¹⁰ in Fig. 2, and take the form of eye-bolts anchored on the tie-rod a². Tubular spacers a³, are then provided between the eye-bolts a¹⁰—a¹⁰, and also between them and the frame members. 45

As a holding means which cannot jar loose, as threaded bolts and nuts are apt to, and as a means that can also take up any slack consequent on racking strains to which these devices are necessarily subject in customary use, I have provided wedge-keys a⁴—a⁴, split longitudinally after the manner of cotter pins, as shown in the detail Fig. 5. Extending upward from the plate a, is a short hollow standard A³, exteriorly threaded. Telescoping in this standard is a rod or short bar e⁶, having a laterally extended head or circumferential flange e⁷, at its upper end, which head or flange abuts against the under side of the guide-rail member E, as shown in 55 Fig. 3.

A⁴ is a nut on the threaded standard A³, in the form of a cup or socket and provided with radial holes for the employment of a lever or turning bar.

60 J is a helical spring seated in the socket

A⁴, with its upper end abutting against the under side of the flange e⁷, as is clearly shown in Fig. 3.

It is to be understood that, except for special purposes, a similar track-assembly to that described, occupies a corresponding position on the opposite side of the complete machine, like the two pairs of wheels in an ordinary spring-mounted four-wheel vehicle.

Hitherto, under present practice and construction, in the endless chain-track type of vehicle, no two of the (longitudinally disposed) carrying wheels simultaneously bear an equal proportion of the load. As the machine progresses on ground of normally uneven contour and hardness, the load shifts from one bearing wheel to the next with a succession of shocks due to surface inequalities; and, in thus shifting from wheel to wheel the load is momentarily transferred to the track chain as an upthrust between the peripheries of the wheels. This means that the load constantly changes from relatively harmless pressure to destructive torsion strains, and the hinges are subjected to a quick succession of violent wrenches resulting in rapid deterioration of the track-chain. Under these conditions high speed of travel comparable to round wheel vehicles, is practically impossible.

In traveling over uneven ground also, the tractive capability varies continuously, from maximum when the whole wheel base has fairly even ground contact to minimum when passing over a hummock. Thus the effective wheel-base tractive area can have little or no calculable relation but only a hit-or-miss approximation to the pulling power of the machine.

In the operation of my invention the wheels G—G¹, support the load resting on frame, and due to the fact that there are but two, (the twin-wheels being deemed a unit), the load is equally divided between G and G¹, as in an ordinary spring-mounted four-wheel road wagon or a four wheel truck of a stationary track vehicle. No load, as such, comes on the antifriction rollers F¹, on the ground-run of the track-chain, but only such pressure as is sufficient to maintain the tractive ground-contact of the tread-shoes f², between the peripheries of G—G¹, and even this pressure is cushioned resiliently by the section e², of the guide-rail.

Traveling over rough surfaces the spring I, cushions the shock of meeting obstructions, while bridge rail e², resiliently conforms to uneven contours and provides uniform tractive contact over the whole length of the wheel-base, at the same time the yielding of section e², avoids shocks on the hinge-pins and relieves the chain track from racking strains of kinking at the hinges. In other words, the ground-run of the track-chain, (on normally variable surface), is a

smoothly undulating track instead of as heretofore, a succession of angularities formed by the upthrust of the links at their hinges.

5. The track-chain F, travels on its rollers F¹, with antifriction smoothness around the guide-rail E, engaging and leaving the power wheel D, and also the idler curvature of the guide rail at the front end without the 10 customary jar. The track-chain F, is maintained at a uniform adjusted tension by the adjustable spring J, in coaction with the upper member E, of the guide-rail.

In the various ways above described, the 15 devices of the present invention obviates and prevents the jars and strains which under ordinary practice and construction are permitted and are mechanically endurable only at the cost of speed, necessitating the slow 20 speeds customary heretofore in the chain-track type of vehicle. The present described construction provides a resilient two-point support extended wheel-base for the track-assembly with the upward flexure of the 25 track-chain resiliently controlled between the support points, a result never heretofore accomplished; and thus is attained a self-laying-track vehicle inherently capable of high speed.

30 In view of these pioneer departures from present accepted practice and construction, I do not desire to be limited to the particular expressions of my invention used herein for illustrative purposes, nor to be limited 35 in any other way than in accord with a liberal interpretation and the reasonable import of the claims which follow and

I claim:

1. A load-bearing track-assembly for vehicles comprising an endless chain-track its 40 lower run adapted to ground support with means to maintain its upper and lower folds in the same plane of travel, a truck between the folds of the chain having load-bearing 45 track-wheels travelable upon the ground run and spaced apart to form a two-point support wheel-base for the assembly, and guide means coacting with the ground run of the chain between the peripheries of the load-bearing track-wheels to control its upward flexure.

50 2. In a track assembly for vehicles, an endless chain of tread shoes with tracks thereon raised above their inner surface, 55 load-bearing wheels travelable upon the ground run of the rails and dirt excluding rail-cover means disposed above the track-rails and below a plane tangential to the upper arcs of the load-bearing wheels.

60 3. A load-bearing track-assembly for vehicles comprising an endless chain-track its lower run adapted to ground support with means to maintain its upper and lower folds in the same plane of travel, a truck movable 65 independently of said means between the

folds of the chain having load-bearing track-wheels travelable upon the ground run spaced apart to form a two-point support wheel-base for the assembly, and a guide coacting with the ground run of the chain between the peripheries of the load-bearing wheels to control its flexure.

4. A load-bearing track-assembly for vehicles comprising an endless chain-track its lower run adapted to ground support with means to maintain its upper and lower folds in the same plane of travel, a truck between the folds of the chain having load-bearing spring-opposed track-wheels travelable upon the ground run spaced apart to form a two-point support wheel-base for the assembly, and means coacting with the ground run of the chain between the peripheries of the load-bearing track-wheels to control its flexure.

5. A load-bearing track-assembly for vehicles comprising an endless chain-track its lower run adapted to ground support with means to maintain its upper and lower folds in the same plane of travel, a truck between the folds of the chain having load-bearing track-wheels travelable upon the ground run spaced apart to form a two-point support wheel-base for the assembly, and resilient means coacting with the ground run between the peripheries of the load-bearing track-wheels to resiliently control its upward flexure.

6. A load-bearing track-assembly for vehicles comprising an endless chain-track with antifriction rollers journaled thereon its lower run adapted to ground support with means to maintain its upper and lower folds in the same plane of travel, a truck between the folds of the chain having spring-opposed track wheels travelable upon the ground run spaced apart to form a two-point support wheel-base for the assembly, and resilient means coacting with the antifriction rollers of the chain between the peripheries of the load-bearing track-wheels to control its upward flexure.

7. In a track-assembly for vehicles an endless chain-track, independently movable spring-pressed load-bearing wheels travelable upon the ground run of the chain spaced apart to form a two-point support wheel-base for the assembly, and resilient means to control the upward flexure of the track between the points of support.

8. In a track-assembly for vehicles, an endless chain-track, a wheel near one end, an oppositely disposed curved member coacting with the wheel to maintain the upper and lower folds of the chain-track in the same plane of travel, support-wheels travelable upon the lower fold of the track intermediate of the wheel and curved member the support-wheels spaced apart to form a two-point-support wheel base for the assem-

bly and means tangent to the lower peripheries of the support-wheels to control the flexure of the chain between the points of support.

5 9. In a track-assembly for vehicles, an endless chain-track, a wheel near one end, an oppositely disposed curved member co-acting with the wheel to maintain the upper and lower folds of the chain-track in the

10 same plane of travel, spring-controlled sup-

port-wheels travelable upon the lower fold of the track intermediate of the wheel and curved member the support-wheels spaced apart to form a two-point-support wheel base for the assembly and means tangent to the lower peripheries of the support-wheels to control the flexure of the chain between the points of support. 15
